UNITED STATES PATENT OFFICE

ALFRED GERHOLD, OF HAGGERSTON, LONDON, ENGLAND.

BRUSH.

1,071,614.

Specification of Letters Patent.

Patented Aug. 26, 1913.

Application filed June 27, 1911. Serial No. 635,604.

To all whom it may concern:

Be it known that I, ALFRED GERHOLD, a subject of the King of Great Britain, residing at 17 Angrave street, Haggerston, in the county of London, England, have invented new and useful Improvements in Brushes, of which the following is a specification.

This invention relates to brushes and their manufacture.

It is a purpose of the invention to produce a brush from which the hairs or bristles can not become loosened through any ordinary usage.

To this end the invention comprises a method of manufacture according to which the bristles or hairs are turned over a bar or other object and then compressed together. The brush thus produced provided with a suitable handle constitutes the object of the invention.

The invention is illustrated in the accompanying drawings in which—

Figure 1 is a longitudinal vertical section of the brush; Fig. 2 is a longitudinal vertical section on a plane at right angles to the plane of Fig. 1; Fig. 3 is an elevation partly in section of a different type of brush; Fig. 4 illustrates a further modification in the securing of the bristles.

The form of construction shown in Figs. 1 and 2 is particularly suitable for cleaning engines for use on motor cars and such purposes, though it is also suitable for painting and so forth. Conveniently the brush is made with a metal, *e. g.*, iron handle 1 for this can be bent to any desired shape. One end of the metal handle is bent into a hook 3 completely or almost completely closed so as to form a loop. The hairs or bristles 4 are arranged in a bunch and cut to a suitable and even length. They are then bent around the hook 3 as may be clearly seen in Fig. 3. Both ends of the bunch of hairs or bristles therefore become ends of the brush, in other words, the brush presents twice as many points as there are hairs or bristles in its composition. The hairs or bristles thus bent around the hook 3 are compressed and clamped or secured in such bent position in any desired fashion.

In Figs. 1 and 2 such clamping or securing is attained by winding on the handle 1 and around hook 3 and the root of the brush proper, wire 5 of iron or other material. 55 This is wound tightly on the bristles being if desired held together during the process in a vise. When the winding is completed the wires are preferably soldered together and more or less coated with solder as indicated at 6, so as to present the appearance of a solid casing. It will be clear that this construction practically prevents any withdrawal of the hairs or bristles in ordinary use. If a hair is to be withdrawn not only 65 has it to be pulled around the corner as it were, which alone results in great resistance, but its two ends are compressed toward each other so that very great friction is interposed almost throughout its length to any 70 motion. In general the hairs or bristles will break rather than come out.

Fig. 4 shows the invention applied to another type of brush commonly employed in white-washing and such large scale operations. There is again a metal handle 8 which is suitably bent so as to form a grip and also has loops or hooks 9 in this case not completely closed. The hairs or bristles 10 are wound over the two loops in separate 80 bundles. Wire 11 is then wound around each bundle and if desired around the two so as to compress the bristles together and secure them substantially as in Figs. 1 and 2. If desired the bristles or hairs may be 85 bent more than once around the bar, hook, loop or the like which retains them. This is indicated diagrammatically in Fig. 4.

It will be clear that the invention may be applied to almost all brushes of ordinary 90 type with such modifications as the shape and normal structure of the brush necessitates.

What I claim is:—

1. A brush consisting of brush material 95 looped intermediate its length, a metallic strip having at one end a loop to receive the looped portion of the brush material, and a wire winding fitting over the looped portion of the brush material and compressing said material.

2. A brush consisting in the combination

of a bundle of brush material, a metal handle having one end formed as a hook to grip said bundle tightly intermediate its length, wire wound upon said handle and over said 5 brush material and hook and solder coating said wire to convert the latter into a complete casing.

In testimony whereof I have signed my name to this specification in the presence of two subscribing witnesses.

ALFRED GERHOLD.
